Inventor,

John R. Risdon,

By his Attorney

Franklin H. Long

UNITED STATES PATENT OFFICE.

JOHN R. RISDON, OF WASHINGTON, DISTRICT OF COLUMBIA, ASSIGNOR OF
ONE-HALF TO FRANKLIN H. HOUGH, OF SAME PLACE.

COMPOSING-STICK.

SPECIFICATION forming part of Letters Patent No. 393,267, dated November 20, 1882.

Application filed February 25, 1882. Serial No. 265,277. (No model.)

To all whom it may concern:

Be it known that I, JOHN R. RISDON, a citizen of the United States, residing at Washington, in the District of Columbia, have invented 5
certain new and useful Improvements in Composing-Sticks; and I do declare the following to be a full, clear, and exact description of the invention, such as will enable others skilled in the art to which it appertains to make and use 10
the same, reference being had to the accompanying drawings, and to the letters and figures of reference marked thereon, which form a part of this specification.

This invention relates to certain new and 15
useful improvements in composing-sticks of that class in which the knee is provided with a means for holding it in its adjusted position; and it has for its object to simplify and cheapen the construction and render it much 20
more easy and efficient in operation.

The novelty resides in the peculiar combinations and in the novel construction, arrangement, and adaptation of parts, all as more 25
fully hereinafter described, shown in the drawings, and then particularly pointed out in the claims.

I dispense with the pivoted lever on the inner or top face of the knee and provide upon the outside of the stick push-buttons, actuating dogs or lugs, which are in convenient 30
position to be operated by the fingers of the hand by the same movement that moves the knee to a different position, and as the fingers are removed after adjusting the knee the same 35
is instantaneously locked in its adjusted position. I also provide a gage, by means of which the knee may be adjusted on a desired "em" or on one-half "em," using two independent dogs or lugs, one for the "ems" 40
and the other for the half "ems," as will be more fully hereinafter set forth. The operating parts are out of sight, protected from the dust and moisture, whereby they are not liable to injury from either of these causes, and also 45
imparting to the device a comely appearance.

In the accompanying drawings, which, with the letters of reference marked thereon, form a part of this specification, is clearly illustrated what I at the present time consider the 50
preferable form of my improvement; but I do

not wish to be confined to the exact construction therein shown and hereinafter described, as the same may be varied without departing from the spirit of my invention.

In the drawings, Figure 1 is a perspective 55
view of a composing-stick embodying my improvements. Fig. 2 is a top plan of the same, with parts broken away and partly in section. Fig. 3 is a transverse section of the same on line *xx* of Fig. 1.

Like letters indicate similar parts throughout the several views.

Reference being had to the details of the drawings, A designates the bottom or base plate, B the end wall or fixed jaw, and C the 65
back wall, of a composing stick formed of any suitable material and of well-known shape. The rear or outer face of the back wall of the stick is formed with a plurality of indents, *a* and *b*, as clearly shown in Fig. 1. These indents extend nearly the entire length of the back wall, and are arranged so that the distance between the indents in each line *a* or *b* correspond with the width of an em of type, and the indents in one line are arranged mid- 70
way of the space between the indents of the other line. From this arrangement it will be seen that I have two gages representing ems or ens. The upper face of the back wall, C, is preferably provided with indicating-lines *c*, 75
corresponding with the indents *a* and *b*, and serving as a guide to the eye in adjusting the knee; but this index is not necessary, and it may sometimes be omitted.

The knee or movable jaw D is of ordinary 85
construction, except as hereinafter specified. The branch *d* thereof, which fits against the back wall of the stick, is formed with a raised portion, *e*, extending above the said back wall, and this raised portion is formed with a dovetailed 90
recess, in which fits a correspondingly-shaped flange, *f*, of the casting E, which is secured therein by means of the screws *g*, or other equivalent means, or it may be made to be held therein by reason of the engagement of the walls 95
of the flange with those of the recess without the employment of other securing means. This casting is formed longitudinally with a slot, *h*, to receive the back wall of the stick, and these parts should be so fitted as to permit one part to 100

slide upon the other easily, and yet allow no loose play. The flanges *i* and *j*, which embrace the top and bottom, respectively, of the back wall, serve as guides for the casting and aid in preventing loose play thereof.

5 *k* is a pin secured vertically in said casting, and on this pin within the casting are pivoted two dogs or lugs, *F* and *G*, extending in opposite directions, and each provided with 10 a thumb-piece or push-button, *F'* *G'*, respectively, which extend through openings *l m* in the casting, as shown. These dogs or lugs are arranged upon different vertical planes, the upper dog, *G*, engaging the upper row, *b*, 15 of indents in the back wall of the stick, and the other dog, *F*, engaging the lower row, *a*, of indents.

15 *n* and *o* are flat springs secured within the casting and acting upon the dogs or lugs *F* and 20 *G*, respectively.

I prefer to cast the knee with an angular brace-rod, *H*, which materially strengthens it and allows of the use of a very light knee; but of course this is immaterial to the operation 25 of the parts above described.

It may at times be found desirable to provide the back wall of the stick with but a single line of indents corresponding in distance apart to the em of the type used, or of ens, as 30 the case may be, in which instance but a single dog or lug would be necessary, as will be readily understood; but it would be arranged in substantially the same manner as above described and would be within the scope of my 35 invention.

35 I deem it important that the indents be upon the outer face of the back wall, for by this arrangement the slotting of the back wall is avoided, as will be readily understood.

40 Having thus described my invention, what I claim to be new, and desire to secure by Letters Patent, is—

1. The combination, with the body of a composing-stick having the outer face of its back 45 wall indented, and the knee, of a pivoted dog on said knee engaging the outer face of the back wall of the stick, substantially as described.

2. The combination, with the body of a composing-stick having the outer face of its back 50 wall indented, and the knee, of an inclosed pivoted dog on said knee engaging the outer face of the back wall of the stick, substantially as and for the purpose specified.

3. The combination, with the body of a composing-stick, the outer face of the back wall of which is provided with a series of indents, and the movable knee, of a casting carried by said knee and arranged outside of said body, and a dog pivoted in said casting outside said body 60 and engaging said indents, substantially as described.

4. The combination, with the body of a composing-stick, the back wall of which is formed with two rows of indents, of the movable knee, 65 a casting secured to said knee, and two reversely-arranged dogs pivoted in said casting upon different vertical planes and engaging said indents, substantially as described.

5. The combination, with the body of the 70 stick, of the knee having a raised portion provided with a recess, as described, a casting having a flange secured in said recess, and a dog pivoted in said casting and engaging the back wall of the body, as set forth.

6. The combination, with the body of the 75 stick and the knee, of the casting carrying a pivoted dog engaging the back wall of said body secured to the knee and formed with flanges *i j*, engaging the top and bottom of said 80 back wall, substantially as and for the purpose specified.

7. The combination, with the body of the 85 stick and the knee, of the casting secured to said knee and movable on the back wall of said body, and the dogs pivoted in said casting and provided with projections extended through openings in said casting, substantially as shown and described.

In testimony whereof I affix my signature in 90 presence of two witnesses.

JOHN R. RISDON.

Witnesses:

MYER COHEN,
FRANKLIN H. HOUGH.
